UNITED STATES PATENT OFFICE

154,250

DESIGN FOR A PRINTED FABRIC

Bernard Eckstein, New York, N. Y., assignor to
The B. V. D. Corporation, New York, N. Y., a
corporation of Delaware

Application June 22, 1948, Serial No. 147,115

Term of patent 3½ years

(Cl. D92—1)

To all whom it may concern:

Be it known, that I, Bernard Eckstein, a citizen of the United States, residing in New York city, in the county of New York and State of New York, have invented a new, original, and ornamental Design for a Printed Fabric, of which the following is a specification, reference being had to the accompanying drawing, forming a part thereof.

The figure is a plan view of a printed fabric showing my new design.

The dotted lines on the drawing outline a design unit, which unit is repeated in regular succession, as indicated by the extensions beyond the unit boundaries.

I claim:

The ornamental design for a printed fabric, as shown and described.

BERNARD ECKSTEIN.
